VALVE

William B. Drury, Providence, R.I., assignor to
Taco, Inc., a corporation of New York

Filed Nov. 21, 1962, Ser. No. 72,576

Term of patent 14 years

(Cl. D91—3)

Fig. 2

Fig. 1

Fig. 3

Fig. 4

FIG. 1 is a side elevation view of a valve, showing my new design;

FIG. 2 is a rear view of the valve;

FIG. 3 is a front view of the valve; and

FIG. 4 is a top view of the valve.

The side opposite that shown in FIG. 1 is a mirror image thereof and the undisclosed bottom of the valve is open.

I claim:

The ornamental design for a valve, substantially as shown and described.
